[57] CLAIM

The ornamental design for a stanchion component half of a two-part assembly which functions as a post to receive slotted strips for holding shelf brackets, as shown and described.

DESCRIPTION

FIG. 1 is a transverse cross-section of a stanchion component half of a two-part assembly which functions as a post to receive slotted strips for holding shelf brackets, showing our new design;

FIG. 2 is a perspective view thereof, from below; and,

FIG. 3 is a perspective view thereof, from above.

The irregular far edge shown in FIG. 2 and 3 connotes an article of indefinite length.
